APPARATUS FOR DISCHARGING FIBROUS AND LIKE MATERIALS FROM BULK

James Mundy Baker, Cainscross, Stroud, England, as
signor to Redier Conveyors Limited, Stroud, England

Application May 11, 1953, Serial No. 354,039

12 Claims. (Cl. 214—17)

This invention relates to apparatus for discharging fibrous and like materials from bulk.

When fibrous materials such as raw cotton, hops or asbestos fibre, are stored in bulk they tend to agglomerate, more particularly at the bottom of the bin or equivalent retainer, for the material at the bottom is compressed by the weight of the material above. As a result the smooth and controlled delivery of fibrous materials from the bottom of the bulk constitutes a difficult problem, for such materials have no propensity to flow, or do so only in an erratic and unpredictable manner.

It is the object of the invention to provide an improved feeding means for fibrous materials which is found to operate satisfactorily and to be readily controllable, the feeding means efficiently separating the particles of fibrous material and delivering them in a substantially constant stream.

According to the invention an apparatus for delivering fibrous material from a bulk supply disposed within a container includes a rotary detaching member formed with outward projections, which member is traversed across the bulk supply and simultaneously rotated, causing the projections to detach particles from said bulk supply.

There is also provided, according to another aspect of the invention, an apparatus for delivering fibrous material from a bulk supply, comprising a container bounded by a grid-like support against which the material presses, and rotary detaching means including a detaching member which is moved along the outside of the grid-like support and operates to detach particles of the material so that they pass through said grid-like support. Preferably the detaching member operates to pull detached particles of the material through said grid-like support. If desired the detaching member may comprise a rotor carrying a plurality of projections which pass into and out of the openings of the grid-like support as the rotor rotates. The rotary detaching means is usually traversed along the grid-like support in a direction substantially at right angles to the axis of rotation of the rotary detaching means, and the grid-like support normally forms the bottom of the container in which the fibrous material is disposed, the rotary disturbing member being mounted underneath the grid-like support; it may, however, extend upwardly to form a side wall or a part thereof. Thus the grid-like support may comprise a series of bar members secured alongside one another in parallel spaced relationship.

Conveniently the detaching member is rotatably mounted upon carriage means, which latter runs upon rails extending along opposite sides of the grid-like support. Thus driving means for the carriage means may comprise an endless chain or equivalent to which said carriage means is attached and which is driven with a reversing motion to cause the carriage means to traverse forwards and backwards along the length of the grid-like support.

Preferably an electric motor driving the rotary detaching member is reversed at the end of each journey made by the carriage means, thereby starting the next journey in the opposite direction. The detaching means can comprise a rotor of elongated shape extending across the grid-like support, and wherein the carriage means comprise a pair of carriage members carrying the respective ends of the rotor, said carriage members being driven in unison to keep the rotor axis at a substantially constant angle relative to the direction of the traversing

2

motion of the rotor. In the preferred arrangement each carriage is driven by a corresponding endless chain, and these chains are positively connected together by motion transmitting means arranged to keep the carriages in alignment; the motion-transmitting means may comprise a common shaft carrying a pair of sprockets with which the chains respectively engage.

The detaching member may be rotated by any suitable means such as an endless chain extending alongside the grid-like support and running permanently in engagement with the detaching member, or the motion of the latter may be derived wholly from the traversing movement of the carriage means.

The invention is illustrated by way of example in the accompanying drawings, in which:

Figure 1 is a side elevation of a bulk storage and discharging apparatus intended primarily for asbestos fibre;

Figure 2 is a sectional plan, the section being taken on the line 2—2 of Figure 1;

Figure 3 is a fragmentary end elevation of the grid-like support and detaching member, as viewed in the direction of the arrow A, Figure 1, and drawn to a slightly enlarged scale;

Figure 4 is a fragmentary end sectional elevation of one of the carriages of the detaching member, the section being taken on the line 4—4 of Figure 1 and drawn to an enlarged scale;

Figure 5 is a diagrammatic side elevation showing the action of the detaching member; and

Figure 6 is a diagrammatic side elevation of a modified form of mechanism for rotating the detaching member.

The apparatus shown in Figures 1 to 5 has a bin or container 10 which is made with vertical end walls 11a and side walls 11b, and is divided into two compartments 12 and 13 by a double-walled vertical partition 14. The two compartments are fed with fibrous material through inlet ducts or chutes 15 and 16 respectively, the compartments serving as bulk storage means for said material. The container 10 is mounted upon a horizontal girder frame 17 supported upon uprights 18 so that its bottom, which is indicated at 19 is disposed a distance of say two or three feet above the ground surface 20.

The bottom 19 is constructed as a horizontal grid through which the fibrous material is delivered as required under the action of detaching means 21 which will be described hereinafter. Thus the end walls 11a have their lower edges disposed at 22 a short distance above the bottom 19 and they join corresponding outwardly extending horizontal plates 23, the outer edges of which are attached to auxiliary cross girders 24. Attached to each of the plates 23 is a series of brackets 25 composed of short lengths of angle material as shown more clearly in Figure 3, and to the lower edge of these 55 a series of stiff bars or rods 26 are welded, said rods extending from end to end of the bottom 19 in parallel spaced relationship to form the grid-like support carrying the weight of the material in the container 10. At their centres the rods 26 are attached, as by welding, to a corresponding series of inverted L-shaped brackets 25a secured to the bottom 27 of the partition 14. It will be realised that this construction provides between the rods 26 clear spaces which extend continuously from one end of the rods to the other; these spaces are indicated at 28 in Figure 3. As the walls 11a, 11b of the container 10 and also the partition 14 thereof are vertical and smooth, the fibrous material disposed therein slides freely downwards until it rests upon the grid-like support constituted by the rods 26, and as the material is progressively abstracted from between the rods 26 by the detaching means 21, the bulk in the compartments 12 and 13 correspondingly falls.

The detaching means 21 comprises a rotor which is disposed just beneath the bottom 19 and is conveniently constructed as a roller 30 extending horizontally at right angles to the rods 26. It carries at close intervals a series of projections in the form of pointed radial spikes 31 as shown in Figure 2, which are so positioned that they pass upwards into the clear spaces 28 as the roller 30 rotates, the tips of the spikes rising higher than the tops of the rods 26. The roller 30 has an axle portion 32 at each

end and these are pivotally mounted in carriages 33 and 34 respectively by means of bearings 35. The roller 30 is arranged to traverse the bottom 19 in the direction of the rods 26, and for this purpose the carriages 33, 34 are provided with wheels 38 by which they run along rail members 36 and 37 respectively. For bringing about this movement the carriages 33, 34 have corresponding driving chains 39 and 40 each being attached at both ends to the corresponding carriage at 41 so that it, with the carriage, forms an endless loop. The chain 39 extends from the carriage 33, over a sprocket 42 fast upon a cross shaft 43, thence along the underneath of the rail member 36, upwards around a sprocket 44 fast upon a second cross shaft 45 and back along the top of the rail member 36 to the carriage 33. Similarly the chain 40 passes around sprockets 46 and 47 fast upon said cross shafts 43 and 45 respectively, thus keeping the carriages truly in side-by-side alignment as they travel forwards and backwards.

The carriages 33, 34 are constructed in the manner shown in detail in Figure 4. Each comprises a flat rectangular body 48 to the underneath of which a pair of fixed axles 49 are secured, these carrying the wheels 38 by means of ball bearings 50. The corresponding rail members shown at 36, comprises an H-section girder 51 with its web horizontal so that the wheels 38 are guided by the flanges thereof, guide strips 52 of inverted L-section being arranged to extend over the wheels 38 to prevent the carriage from riding up. The bearing 35 is, of course, mounted on top of the body 48, as also is the attachment device 41 for the chain 39; the lower run of the chain 39 rests in a trough 53. A guard plate 54 is held vertically by one or more brackets 55 upon the body 48 and runs close to the side wall 11b so as to prevent fibrous material falling into the rail member 36. All the details so far described also apply to the carriage 34.

In addition the carriage 33 incorporates some of the mechanism used for rotating the roller 30. The shaft portion 32 is extended to receive a sprocket 56 over the top of which an endless driving chain 57 passes. In front and behind the sprocket 56 the carriage is fitted with a pair of freely rotatable grooved guide pulleys 58 and 59 (see Figure 2) underneath which the chain 57 passes so as to maintain a substantial arc of chain engagement around the sprocket 57. Each guide pulley 58, 59 is mounted upon a rod 60 projecting from the body 48. The arrangement of the driving chain 57 is shown more clearly in Figures 1 and 2 and it will be seen that its upper run extends horizontally leftwards, over an idler sprocket 61, then back horizontally to a driving sprocket 62 and back to the sprocket 56 on the roller shaft 32. In order to support the horizontal runs of the chain 57 an upper trough 63 and a lower trough 64 (Figure 4) are attached to the outside of the rail member 36.

In the apparatus illustrated the following means are used for driving the chain 39 to traverse the roller 30, and the chain 57 to rotate the said roller 30. A reversible electric motor 70 (Figure 1) has a sprocket 71 driving a large toothed wheel 72 by an endless chain 73, said wheel 72 being fitted upon the shaft 74 carrying the sprocket 62. Thus the endless chain 57 is drawn around the sprocket 56 causing the spiked roller 30 to be turned continuously in the same direction as the motor 70 is running. A second sprocket 75 on the shaft of the motor 70 is coupled by a chain 76 to a sprocket 77 on the input shaft of a reduction gear unit 78 conveniently embodying a hydraulic slipping clutch or coupling to form speed regulating means, the output shaft of the unit having a sprocket 79 connected by an endless chain 80 to a sprocket 81 fast on the cross shaft 43. Thus the chains 39, 40 connected to the carriages 33, 34 are driven by the cross shaft 43 to travel in the opposite direction to the endless chain 57 driving the spiked roller 30; as a result the carriages 33, 34 travel along slowly beneath the bottom 19 and at the same time the roller 30 is turned relatively rapidly in such a direction that the spikes 31 at the top are advancing in the direction opposite to that of carriages 33, 34. A reversing switch or switch system (not shown) is provided in connection with the motor 70 for the purpose of reversing its direction automatically as the carriages 33, 34 reach the end of each journey across the bottom 19; thus the direction of rotation of the roller 30 is reversed to suit the changed direction of travel.

The action of the detaching means comprising the spiked roller 30 is shown in Figure 5. The fibrous mate-

rial rests in a mass upon the rods 26 as indicated at 85, but its agglomerating properties are too strong to allow any substantial amount to fall freely between the rods 26. As the roller 30 slowly advances beneath the bottom 19, say in the leftwards direction as shown, the roller 30 is turning clockwise so that the spikes 31 pass upwards between the rods 26 and comb the fibrous material, portions of the latter being pulled or dragged rearwards and downwards between the rods so as to be free to fall as a shower of separated particles 86. A suitable conveyor (not shown) is usually fitted underneath the apparatus in the space 87 between the uprights 18 and carries off the separated fibrous material to the desired place for use, packing, treatment or other operation. The bulk material in the compartments 12, 13 progressively slides down the smooth vertical walls and readily settles upon the rods 26 of the bottom 19 as the material is gradually removed by the detaching member 30, 31. In order to avoid jamming of the material against the end walls 11a of the container as the roller 30 reaches the end of each journey, the length of travel is so arranged that the roller passes beneath the havens formed by the L-shaped brackets 25. In Figure 1 the roller 30 is shown in one such end position. Thus any fibrous material being acted upon by the spikes 31 can get clear before the roller reverses on its next journey.

A modified method of driving the detaching member 30, 31 is shown diagrammatically in Figure 6, a separate drive for bringing about the rotation being avoided. The roller 30 is again mounted on carriages 33, 34 which are moved forwards and backwards by a pair of chains 39, 40 as before, the same reference numerals being used in the figure, where applicable. A toothed rack 88 is fixed horizontally and is engaged by a pinion 89 on the shaft of the roller 30 so that in this example as the roller is moved towards the right at a given speed, the spikes 31 at the top also move towards the right but at a much greater speed. Similarly leftward travel of the roller 30 is accompanied by speedier leftward movement of the top spikes 31.

It will be understood that the above details are given by way of example only and that various modifications in the details of construction and the arrangement of the parts may be made. Thus, in some cases it may be desirable to provide two or more rollers which are arranged to operate in tandem, the spikes being so fitted as to engage the material to equal depths, or to depths which progressively increase. If desired the spikes of the detaching means may be of curved or other shape, as best suits the material to be handled.

What I claim is:

1. An apparatus for delivering fibrous material from a bulk supply, comprising a container including a grid-like support against which the material presses, carriage means guided to run along a path extending parallel with the grid-like support, rotary detaching means carried by said carriage means, and driving means for rotating the rotary detaching means as it moves with the carriage means along the grid-like support, said rotary detaching means projecting through said support to draw the fibrous material therethrough.
2. An apparatus as claimed in claim 1, having rails extending along opposite sides of the grid-like support, and upon which the carriage means is mounted.
3. An apparatus for delivering fibrous material from a bulk supply, comprising a container bounded by a grid-like support against which the material presses, detaching means including a rotary detaching member which is moved along the outside of the grid-like support and operates to detach particles of the material so that they pass through said grid-like support, carriage means for the rotary detaching member and driving means for the carriage means comprising an endless chain or equivalent to which said carriage means is attached and which is driven with a reversing motion to cause the carriage means to traverse forwards and backwards along the length of the grid-like support.
4. An apparatus as claimed in claim 3, including an electric motor which drives the rotary detaching member and is reversed at the end of each journey made by the carriage means, the rotary detaching member thereby rotating in the opposite direction while making the next journey.
5. An apparatus as claimed in claim 4, in which the rotary detaching member comprises a rotor of elongated

shape extending across the grid-like support, and the carriage means comprise a pair of carriage members carrying the respective ends of the rotor, said carriage members being driven in unison to keep the rotor axis at a substantially constant angle relative to the direction of the traversing motion of the rotor.

6. An apparatus as claimed in claim 5, having a pair of endless chains driving the respective carriage members and motion transmitting means positively connecting these chains together to keep the carriages in alignment.

7. An apparatus as claimed in claim 5, in which the said motion transmitting means comprise a common shaft, and a pair of sprockets which are mounted on said common shaft and with which the chains respectively engage.

8. An apparatus for delivering fibrous material from a bulk supply, comprising a container bounded by a grid-like support against which the material presses, detaching means including a rotary detaching member which is moved along the outside of the grid-like support and operates to detach particles of the material so that they pass through said grid-like support, and an endless chain for driving the rotary detaching member, which endless chain extends alongside the grid-like support and engages with a sprocket driving the detaching member.

9. An apparatus for delivering fibrous material from a bulk supply, comprising a container bounded by a grid-like support against which the material presses, detaching means including a rotary detaching member which is moved along the outside of the grid-like support and

5

operates to detach particles of the material so that they pass through said grid-like support, a fixed member, and gearing which connects the rotary detaching member to said fixed member so that the traversing motion of said rotary detaching member causes it to be rotated.

10. An apparatus as claimed in claim 9, wherein the fixed member comprises a rack, and the detaching member is provided with a pinion which engages and runs along said rack.

11. An apparatus as claimed in claim 4, wherein a series of containers are arranged end to end and have a common grid-like support comprising bars extending along the series of containers to form their bottom walls, the rotary detaching member being driven to traverse the respective containers one after the other in succession.

12. An apparatus as claimed in claim 8, in which the rotary disturber member is mounted upon carriage means driven to move backwards and forwards along the length of the grid-like support, and a driving motor imparts motion to the said endless chain, the rotary disturber member being caused to rotate by the relative motion between this endless chain and the carriage means.
